THEFT PREVENTION DEVICE

Fred V. Maddin, Tulsa, Okla.

Application September 22, 1933, Serial No. 690,595

9 Claims. (Cl. 220—86)

The invention relates to theft prevention devices, particularly adapted for use in connection with the filling pipe of a tank for storage of gasoline at filling stations, and has for its object to provide an obstruction member within the filling pipe at a substantial distance from the intake end thereof and removable means lock controlled and adapted to be inserted in the filling pipe and having rotatable lugs adapted to be placed in interengagement with the obstruction member whereby said obstruction member may be removed from the filling pipe when it is desired to refill or empty the tank through the filling pipe.

10 A further object is to provide the obstruction member with a downwardly extending member adapted to engage the bottom of the tank for limiting the downward movement of the obstruction member in the filling tank to a predetermined position.

15 A further object is to upwardly bevel the interengaging portions of the obstruction member, thereby preventing the removal of the member by inserting a hooked instrument into the filling pipe.

20 A further object is to provide the lock casting with a tubular extension in which the rotatable lock bolt is rotatably mounted in an off-center position so that the interengaging lugs carried thereby may be rocked or rotated into locking engagement with arcuate grooves in the inner periphery of the obstruction member for removing the obstruction member or into the lines of the tubular member, thereby allowing 25 removal of the obstruction removing device when desired without removing the obstruction or vice versa.

25 A further object is to provide the obstruction member with a chamber of substantially the same size as the tubular member of the removing device, thereby insuring interengagement of the locking lugs in the arcuate slots in the obstruction member by preventing lateral displacement of the tubular member.

30 A further object is to provide the lug end of the removing device with an interengaged cap locked thereon by the lugs, thereby preventing copying of the locking combination by unauthorized persons when the device is not in use, for instance in the filling station.

35 With the above and other objects in view the invention resides in the combination and arrangement of parts as hereinafter set forth shown in the drawing, described and claimed, it being understood that changes in the precise embodiment of the invention may be made within the scope of what is claimed without departing from the spirit of the invention.

40 In the drawing:

45 Figure 1 is a vertical transverse sectional

view through a portion of a conventional form of gasoline storage tank, a filling pipe and the obstruction device.

Figure 2 is a vertical transverse sectional view in perspective of the obstruction device, the obstruction remover and a portion of the filling pipe.

Figure 3 is a detail perspective view of the lower end of the obstruction remover.

Figure 4 is a horizontal sectional view taken 10 on line 4—4 of figure 2.

Figure 5 is a detail perspective view in vertical transverse cross section of a portion of the removal device and a removable protecting cap carried thereby.

Referring to the drawing, the numeral 1 designates a gasoline storage tank of the type which is embedded in the ground 2 and 3 an upwardly extending filling pipe carried by the tank. Filling pipe 3 is provided with removable cover 4 on its upper end, held in position by a lock 5. It has been found that unauthorized persons may easily obtain access to the tank through the filling pipe 3 by twisting the lock 5 from position or otherwise breaking the cap 4, and after which it is only a matter of inserting a pipe and pumping the gasoline from the tank. Theft operations of this character are often carried on by filling station operators, and in which case the tank is usually filled with an inferior grade 30 of gasoline, and to obviate this difficulty, the present device is primarily designed.

To prevent unauthorized persons from removing gasoline from the tank 1 through the filling opening 2 an obstruction 6 is provided 35 which is adapted to be placed in the filling pipe 3 at a substantial distance from the upper end thereof, so it can not be reached with ordinary tools or implements. The obstruction 6 is provided with an extension 7 which extends downwardly into the tank 1 and rests on the bottom thereof at 8. The extension 7 has sufficient rigidity whereby it will not bend or collapse if an instrument is inserted in the filling pipe 3 against the obstruction 6 for driving the obstruction into the tank and from the filling pipe. The upper end of the obstruction extension 7 is threaded at 9 into the obstruction as clearly shown in Figure 2. It will be noted that the obstruction 6 is of slightly smaller diameter than 40 the filling pipe, however this is only for a working fit incident to the rough interior periphery of the filling pipe.

The obstruction 6 is provided with a chamber 50 in its upper side, and which chamber terminates at its upper end in a bevelled outward flared portion 11 for guiding the lower end of the tubular extractor member 12 axially into the chamber 10 when lowered into filling pipe for removing the obstruction. This action is fur- 55 60

ther insured by providing the lower end of the tubular member 12 with a bevelled surface which cooperates with the bevelled surface 11. The tubular member 12 is of a substantial length 5 for insertion into the filling pipe for an inter-engaging operation with the obstruction 6 and terminates at its upper end in a lock casing 14 adapted to be grasped by the operator during an obstruction removing operation.

10 The lock casing 14 has disposed therein a conventional form of key controlled mechanism controlled by the key 15 for unlocking and rotating the lug carrying rod 16 which extends downwardly through the tubular extension 12 and has a bearing 17 in the lower end of the extension. Rod 16 terminates at its lower end in a rectangular portion 18 having mounted thereon in spaced relation locking lugs 19, which, when the rod 16 is rotated, move outwardly to a position beyond the peripheral lines of the tubular member 12 and into the arcuate grooves 20 in the inner periphery of the chamber 10 for forming an interengaging connection between the obstruction removing device and the obstruction, thereby allowing removal of the obstruction from the pipe 3 when it is desired to refill the tank 1. It will be noted that the tubular member 12 is of substantially the same diameter as the chamber 10 of the obstruction, 30 therefore there will be no danger of a lateral movement of the lower end of the tubular member 12 in the chamber 10 during the interengagement of the lugs 19 in the grooves 20. It is obvious that any number of lugs 19 may be used, and any number of grooves 20 and positioned at different distances apart, and that such combinations can be varied by increasing or reducing the number of spacing washers 21 interposed between the lugs 19, the tubular extension 40 12 and the retaining screw 22. Applicant does not limit himself in this particular. Operating rod 16 is eccentrically mounted to one side of the center of the tubular member 12, hence it will be seen that when the lugs 19 are moved 45 to their unlocked positions as clearly shown in dotted lines in figures 2 and 3, they will be within the peripheral lines of the tubular member 12, thereby allowing removal of the removing device.

When the obstruction removing device is not 50 in use, it may be kept in the filling station with the key 15 removed. However, to prevent anyone from observing the number of lugs 19 or this particular mechanism or duplicating the combination, a cap 23 is provided which is locked 55 on the tubular member 12 as clearly shown in Figure 5 with the lugs 19 in the arcuate grooves 24 in the inner periphery of the cap, therefore it will be seen that it will be impossible for an unauthorized person to remove the cap, observe or 60 duplicate the combination, consequently the obstruction removing device may be left around the filling station with safety. The upper edges of the groove 20 are bevelled as shown at 25 in Figure 2, thereby preventing the insertion of a hooked instrument into engagement therewith for unauthorized removal of the obstruction as it is obvious that the bevelled edges would prevent the obtaining of a purchase or hold on the device.

70 From the above it will be seen that a theft prevention device is provided for use in connection with storage tanks wherein an obstruction is removably placed in the filling pipe and that a removing device is provided in connection 75 therewith whereby the obstruction can be easily

and quickly removed from its position. Also that a housing device is provided in connection with the removing device which will prevent unauthorized persons from observing and duplicating the interengaging combination of the parts. 5

The invention having been set forth what is claimed as new and useful is:

1. The combination with a removable abutment in a filling pipe of a gasoline storage tank, of means for removing said abutment, said means comprising an elongated tool, said tool comprising a tubular member, one end of said member extending into a chamber of the abutment, a lock casing carried by the other end of said tubular member, an eccentrically mounted rotated rod in said tubular member and extending into the chamber of the abutment, said rod being lock controlled, a plurality of lugs carried by said rod within the chamber of the abutment and movable into registering grooves in the chamber of the abutment, said lugs being movable to positions outside the lines of the tubular member.

2. A device as set forth in claim 1 including upper bevelled edges in the groove in the chamber of the abutment. 25

3. A device as set forth in claim 1 wherein the upper end of the chamber of the abutment is flared.

4. A device as set forth in claim 1 including a flared upper end to the abutment chamber and a bevelled lower end on the tubular member.

5. The combination with a filling pipe abutment removing tool having means for locking the same to an abutment in a filling pipe, of a housing for the locking portion of said tool entirely concealing the same and locked thereto by its locking means.

6. The combination with a normally unobstructed filling pipe of a storage tank, said pipe having an upwardly disposed discharge end, of an abutment in said filling pipe spaced from the discharge end thereof and of substantially the same size of the interior of the pipe, whereby flow of liquid through the filling pipe is blocked, the spacing of the abutment from the discharge end of the pipe forming means whereby said abutment can not be reached by an ordinary tool, a rigid member carried by said abutment and extending into the tank and into engagement with the tank, said abutment being solely limited in its movement towards the tank by said rigid member.

7. A device as set forth in claim 6 including means carried by the abutment for receiving a removing tool.

8. The combination with an abutment disposed in a filling pipe and substantially closing the passage therethrough whereby flow of liquid is blocked through the pipe, said abutment being spaced from the discharge end of the pipe a substantial distance whereby it can not be reached by ordinary tools, a tank into which said filling pipe discharges, of a rigid member carried by the abutment and extending into the tank and cooperating with the tank and forming sole means for maintaining the abutment in a predetermined position in the filling pipe.

9. A device as set forth in claim 8 including a bottom carried by the tank and with which the rigid member engages, said tank bottom forming, in connection with the rigid member, sole means for limiting the downward movement of the abutment in relation to the tank.
